(57) **CLAIM**

The ornamental design for a shock mount for microphone, as shown and described.

DESCRIPTION

FIG. 1 is a front, right, and top perspective view of a shock mount for microphone, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a part of a baffle.

FIG. 10 is a partial enlarged view of an area labeled 10 in FIG. 2 comprising a part of an adjustable knob; and, FIG. 11 is a partial enlarged view of an area labeled 11 in FIG. 2 comprising a part of side walls of a base.

The broken lines shown in the drawings are included for the purpose of illustrating portions of the shock mount for microphone that form no part of the claimed design.

The dot dash dot broken lines encircling portions of the shock mount for microphone in FIGS. 1 and 2 and illustrated in enlarged views of FIGS. 9 through 11 form no part of the claimed design.
